ACCORDION

Ernest Bonvicini, Denver, Colo.

Application January 31, 1951, Serial No. 14,046

Term of patent 14 years

(Cl. D56—1)

To all whom it may concern:

Be it known that I, Ernest Bonvicini, a citizen of the United States of America, residing in Denver, in the county of Denver and State of Colorado, have invented a new, original, and ornamental Design for an Accordion, of which the following is a specification, reference being had to the accompanying drawing, forming part thereof.

In the drawing

Fig. 1 is a top plan view of an accordion, showing my new design;

Fig. 2 is a rear elevational view;

Fig. 3 is a left side view. The right side view of the accordion presents substantially the same appearance as the left side view of Fig. 3.

Fig. 4 is front elevational view thereof.

I claim:

The ornamental design for an accordion, substantially as shown and described.

ERNEST BONVICINI.
